(57) **CLAIM**

I claim the ornamental design for a surface attachment device, as shown and described.

DESCRIPTION

FIG. 1 is a top perspective view of a surface attachment device showing my new design;

FIG. 2 is a top plan view thereof;

FIG. 3 is a bottom plan view thereof;

FIG. 4 is a front elevational view thereof; the rear elevational view being a mirror image of FIG. 4;

FIG. 5 is a side elevational view of the left-hand side thereof; the right-hand side elevational view being a mirror image of FIG. 5;

FIG. 6 is a top perspective view of a first alternative embodiment of a surface attachment device showing my new design;

FIG. 7 is a top plan view thereof;

FIG. 8 is a bottom plan view thereof;

FIG. 9 is a front elevational view thereof; the rear elevational view being a mirror image of FIG. 4;

FIG. 10 is a side elevational view of the left-hand side thereof; the right-hand side elevational view being a mirror image of FIG. 10;

FIG. 11 is a top perspective view of a second alternative embodiment of a surface attachment device showing my new design;

FIG. 12 is a top plan view thereof;

FIG. 13 is a bottom plan view thereof;

FIG. 14 is a front elevational view thereof; the rear elevational view being a mirror image of FIG. 14; and,

FIG. 15 is a side elevational view of the left-hand side thereof; the right-hand side elevational view being a mirror image of FIG. 15.
